3 Claims.

(CL. 102—84)

As is known, the application of a suspended wire-like balance-wheel torsion spring arranged along the axis of the projectile to clockwork time fuses for projectiles presents important advantages by comparison with the use of a spirally shaped balance-wheel spring and has already been carried out on repeated instances. It has been found, however, that the provision of such a spring is accompanied by the disadvantage that owing to the inertia prevailing when the projectile is fired off, transient or permanent distortions of the several parts of the clockwork mechanism may take place and these may in turn cause permanent distortions of the balance-wheel spring. These obviously have an unfavorable influence upon the duration of oscillation of the balance-wheel and therefore on the operational accuracy of the entire clockwork mechanism.

Proposals have been made heretofore to obviate such distortions of the balance-wheel spring. Thus for example it was proposed to secure one end of the balance-wheel spring to a resilient carrier. Another proposal consisted in so coupling with longitudinal movability the spring of the balance-wheel to the axis of the latter that the operative length of said spring should keep the same value in spite of the distortion of the parts of the fuse or clockwork mechanism. However, such proposals are not simple to carry into practice, the more so as the entire fuse is of smaller overall size.

An object of the present invention is to provide by extremely simple means an improved balance-wheel torsion spring wherein proper equalization of the operative length of said spring is achieved while the clockwork mechanism is being made or when it is subsequently regulated.

Another object of the invention is to provide an improved balance-wheel torsion spring which while fulfilling the first-cited object affords substantial unsensitivity when the projectile fitted with the clockwork fuse thus equipped is fired off from the gun.

Still another object of the invention is to provide a tape-shaped or wire-shaped balance-wheel spring operating by torsion and having an undulated shape, so that it can without being damaged yield to slight distortions or small longitudinal shifts of one of its securing points with respect to the other parts of the clockwork mechanism.

With these and such other objects in view as will incidentally appear hereafter, the invention comprises the novel structure and combination or arrangement of parts that will now be described

with reference to the accompanying drawing exemplifying the same and forming a part of the present disclosure.

In the drawing:

Figure 1 is partly an elevational view and partly a vertical sectional view showing one form of the improved torsion spring as associated with parts of a clockwork mechanism adaptable to a time fuse for a projectile.

Figures 2, 3 and 4 are fragmentary detail views showing other forms that may be taken by the torsion spring.

As illustrated in Fig. 1, 10 designates the tape-like or wire-like torsion spring which has an undulated or sinuous outline. The lower end of the spring 10 is engaged in a slot formed in the upper end of an upstanding pin 11 and held in said slot by a thimble-shaped bush 12. The pin 11 is carried in a peripherally grooved bearing 13; it has a stepped lower enlargement 14 and forms the axis of an underlying balance-wheel 15 which is supported at some distance from a subjacent hollow carrier or base 16 forming the lower part of the clockwork mechanism which may be of any conventional structure. The balance-wheel 15 is clear of the carrier 16 and may be held motionless during the transportation of the fuse by any conventional lock which is not shown as it forms no part of the invention. This will prevent any premature unwinding of the clockwork mechanism.

The bearing 13 is clamped in the apertured bottom of an upstanding tubular structure 17 which forms the upper part or platen of the clockwork mechanism. In the smooth inner wall 35 of this structure 17 is telescopically engaged the bottom end of a carrying sleeve 18 while the outer wall of said structure 17 is screw-threaded as at 17a to match the inner screw thread of a retaining skirted nut 19 engaged over the externally 40 screw-threaded wall 18a of the sleeve 18. Said wall 18a has a shoulder 18b by which any undue screwing down motion of the nut 19 is precluded.

Mutual rotation of the sleeve 18 with respect to the tubular carrier structure 17 after proper adjustment of the parts is prevented by a grub screw 20 whose shank projects through an adjacent longitudinal groove 18c formed in said sleeve and into contact with its outer wall as shown. The parts 17 and 18 are firmly clamped to each other on completion of their mutual adjustment by another grub screw 21 having a pointed bit engaging into a socket in the sleeve 18. Several screws such as 21 may be provided at different positions if required.

The upper end 10a of the undulated spring 10 projects outside from the top face of the sleeve 18 so that it can be properly gripped by a suitable tool (not shown) while it is handled and set into correct position. An axial bore is provided in the upper part of the sleeve 18 for the passing of the spring 10, a sufficient clearance being left to that effect. Said clearance is filled up by a small lining plate 22 held against the spring 10 by a grub screw 23 forming the upper securing point for the spring 10. The top face of the sleeve 18 has a diametrical cut and a peripheral shoulder defining a notch in which is accommodated a clamping ring 24.

Owing to the provision of the lining plate 22, the spring 10 cannot be damaged by the shank of the securing screw 23 when the latter is driven home.

When assembling the parts, the distance between the points at which the torsion spring 10 is held at its ends may be varied by more or less screwing down the skirted nut 19 upon the screw-threaded wall 18a of the carrier sleeve 18. The required degree of accuracy may be obtained by providing the screw threads 17a and 18a of opposite or differentiated pitch. When proper adjustment has been secured, the parts 17 and 18 may be clamped together by driving the screw 21 into its socket.

Instead of having the undulated or corrugated outline shown in Fig. 1, the torsion spring 10 may be rendered longitudinally resilient by being looped or crooked intermediate its ends as shown by way of examples in Figs. 2, 3 and 4.

In the modification shown in Fig. 2, the spring 10 is formed at any suitable position or positions intermediate its ends with a double counter-elbow or S-shaped loop as shown at 25. In Fig. 3, the spring 10 is formed at any convenient position or positions intermediate its ends with a substantially circular loop 26 situated in a plane more or less parallel to the general direction in which the spring extends. In Fig. 4, the spring 10 is provided at any convenient position or posi-

tions between its ends with a substantially circular or polygonal loop 27 situated in a plane more or less perpendicular to the general direction in which the spring extends.

6 While only one of these loops 25, 26 or 27 has been shown, more than one may be provided in the length of the spring 10 to render it adequately resilient lengthwise.

10 It will be understood that owing to the longitudinal resiliency possessed by the torsion spring owing to its undulated or crooked outline, no damage or variation of its useful length can take place in operation.

15 While several embodiments of the invention have been described and shown, it is to be understood that it is limited solely by the scope of the appended claims rather than by any of the constructional details set forth.

What is claimed is:

- 20 1. In a clockwork time fuse for projectiles, a balance wheel mechanism comprising a bearing, a balance wheel oscillatable in said bearing, a torsion spring connected at one end to said balance wheel at the axis thereof, and a holding member mounted in the fuse opposite said balance wheel and to which member the other end of said torsion spring is connected, said torsion spring consisting of a longitudinal wire having its mass lying substantially in the axis of torsion and having a configuration providing predetermined limited longitudinal resilience greater than that of the wire itself.
- 25 2. A balance wheel mechanism according to claim 1 in which the torsion spring is of undulatory configuration longitudinally between its points of connection.
- 30 3. A balance wheel mechanism according to claim 1 in which the torsion spring comprises straight portions at the ends thereof connected to the balance wheel and holding members respectively and at least one loop intermediate of said straight portions.

GUIDO HÖNGER.
